CLAIM

The ornamental design for a negative-pressure therapy device module, as shown and described.

DESCRIPTION

FIG. 1 is a top and front isometric view of a negative-pressure therapy device module, shown in an environment of use;

FIG. 2 is a bottom and front isometric view thereof;

FIG. 3 is a front elevation view of the negative-pressure therapy device module;

FIG. 4 is a rear elevation view thereof;

FIG. 5 is a right side view thereof;

FIG. 6 is a left side view thereof;

FIG. 7 is a bottom plan view thereof;

FIG. 8 is a bottom and front isometric view thereof; and,

FIG. 9 is a top and rear isometric view thereof.

The broken line showing of the negative-pressure therapy device in FIGS. 1-2 depicts environmental structure and forms no part of the claimed design. All other broken lines in the drawings depict portions of the negative-pressure therapy device module that form no part of the claimed design.
